CONDIMENT DISPENSER

Nicholas Kouralis, 5819 Spruce St., Philadelphia, Pa.

Filed May 31, 1960, Ser. No. 60,784

Term of patent 7 years

(Cl. D44—22)

Fig. 1

Fig. 2

Fig. 1 is a view in side elevation of a condiment dispenser embodying my new design; and

Fig. 2 is a top plan view thereof.

I claim:

The ornamental design for a condiment dispenser, substantially as shown.
